Application April 6, 1935, Serial No. 15,167
In Sweden May 5, 1934

4 Claims. (Cl. 2-237)

This invention relates to an improvement in trousers having a waistband and a front placket or fly, the object of the invention being to provide fastening means whereby it will be possible 5 to hold the garment safely supported upon the wearer while avoiding the use of the ordinary braces or the ordinary belt otherwise used for holding the trousers in proper position.

The invention is especially valuable during 10 the warm season when waistcoat and in many cases also jacket are not worn in every-day use, and also in connection with dresses for tennis, gymnastics and sporting.

According to the invention the waistband on 15 the covering part of the front placket or fly of the trousers is prolonged to a strap provided with one or more buttonholes while on the subjacent part of the placket the waistband has a slit, beyond which, on the inside of the waistband, 20 buttons are fastened, on which the strap is buttoned after that it has been put through the waistband slit. By varying the buttoning of the strap it is possible to secure the proper contraction of the waistband which in each case is required for holding the trousers tight around the 25 waist. Buttons as well as back- and side-straps on the outside of the waistband which otherwise are used on trousers are avoided by this invention whereby the trousers obtain a fine appearance. The device may also be used in connection 30 with an adjustable belt placed in a tunnel in the waistband whereby an increased possibility of suiting the waistband to the width of the waist is obtained as will be more fully explained in 35 the following.

The invention is illustrated by the accompanying drawing which shows some embodiments thereof. Fig. 1 shows a perspective view of the upper part of a pair of trousers with waistband 40 according to the invention and Fig. 2 shows the waistband thereof from the inside. Fig. 3 shows a portion of the waistband of a second embodiment with double waistband strap seen from the outside.

45 In the embodiment shown in Figs. 1 and 2 the trousers, which are a pair of walking trousers 1 having the usual front placket or fly 2, have a waistband 3 which on the covering part of the front placket is prolonged to a strap 4 having one or more buttonholes 5. In buttoning the 50 trousers the strap 4 is put through a slit 6 in the waistband on the subjacent part of the front placket and is buttoned on buttons 7 which are fastened with suitable distances apart on a strap 55 8 sewn to the inside of the waistband and pro-

vided at its rear end with a clasp 9 for holding one end of a belt 10 which to its substantial length is placed in a tunnel in the waistband 3, said belt extending through the greater part of the waistband and with its other end being secured to the waistband as is indicated at 11. In this embodiment the trousers are approximately suited to the waist width of the wearer by a suitable contraction of the belt whereupon a more exact fitting is obtained by buttoning the strap on that of the buttons 7 which just gives the most suitable tightening of the waistband around the waist. If the width of the waist is materially altered during the life of the trousers compensation can be easily obtained by altering 10 the contraction of the belt and the fit of the trousers thus be maintained.

15 In the embodiment shown in Fig. 3 the waistband strap on the covering part of the front placket is double, that is, consists of a band 20 which at its middle part is sewed to the front side of the fly and has two loose ends or straps 4a, 4b, extending toward both sides to the right and to the left. One of said ends or straps is indicated by 4a and corresponds as regards form and 25 arrangement to the strap 4 in Figs. 1 and 2 and is thus buttoned to a strap 8 sewed to the inside of the waistband. The other end or strap 4b, which also has button-holes, is in buttoning the trousers put through a slit 12 in the waistband 30 on the covering part of the trousers' front placket and buttoned on buttons 13 on the inside of the waistband 3. The buttons 13 may be fastened to a reinforcing part 14 secured to the 35 inside of the waistband and corresponding to the strap 8. Said reinforcing part 14 may be secured directly to the fixed end 11 of the belt 10 or may consist of its end which in the latter case is drawn out from the tunnel in the waistband 3 and secured to the inner side of the waistband. 40 It is not necessary to unbutton said strap from the buttons 13 on opening the trousers, in as much as its chief object only is to counteract the pull of the part 4a on the covering part of the front placket and when required to assist 45 in suiting the width of the trousers to the wearer's waist width. In other respects the embodiment shown in Fig. 3 is similar to that shown in Figs. 1 and 2 and similar parts carry the same reference characters. Instead of one band or 50 strap having two free ends 4a, 4b, said two free ends in Fig. 3 may be understood to be two separate straps 4a, 4b, sewed to the covering part of the fly 2 at their adjacent ends to form the double strap.

What I claim is:—

1. A trousers garment having a waistband provided with a slit, a tunnel and a fly, said fly having a covering part and a subjacent part, a strap fixed to said waistband on the covering part of said fly for insertion through said slit, a second strap secured to the inside of said waistband, a variable button-and-hole connection between said two straps, a clasp secured to said second strap, and a belt placed in the tunnel in said waistband, said belt having one end adjustably connected with said clasp, the other end of said belt being secured to said waistband.

2. A trousers garment having a fly and a waistband provided with a tunnel and two slits, said fly having a covering part, means providing two free outer strap end portions extending in opposite directions and fixed to the waistband on the covering part of the fly for insertion through the two slits of the waistband, an inner strap secured to the inside of said waistband, a variable button-and-hole connection between one of said outer strap portions and said inner strap, a clasp secured to said inner strap, a belt placed in a tunnel in said waistband, said belt having one end adjustably connected with said clasp and its other end secured to said waistband, and a button-and-hole connection between the other of said outer strap end portions and said waistband at that end of said belt which is secured to said waistband.

3. A trousers garment having a fly and a waistband provided with a tunnel and two slits,

said fly having a covering part, two free outer strap end portions extending in opposite directions and fixed to the waistband on the covering part of the fly for insertion through the two slits of the waistband, an inner strap secured to the inside of said waistband, a variable button connection between one of said outer strap end portions and said inner strap, a clasp secured to said inner strap, a belt placed in a tunnel in said waistband, said belt having one end adjustably connected with said clasp and its other end fixed to said waistband, a reinforcing member secured to said fixed end of said waistband, and a button connection between the other of said outer strap end portions and said reinforcing member.

4. A trousers garment having a fly and a waistband provided with a tunnel and two slits, said fly having a covering part, a band sewn in its middle part to the covering part of said fly, said band having two free ends forming two outer straps for insertion through the two slits of the waistband, an inner strap secured to the inside of said waistband, a variable button-and-hole connection between one of said outer straps and said inner strap, a clasp secured to said inner strap, a belt placed in a tunnel in said waistband, said belt having one end adjustably connected with said clasp and its other end secured to said waistband, and a button-and-hole connection between the other of said straps and said waistband at that end of said belt, which is secured to said waistband.

WILHELM ADOLF PERSSON.
